UNITED STATES PATENT OFFICE.

LEWIS D. CORTRIGHT, OF HYDE PARK, ILLINOIS, ASSIGNOR TO THE CORTRIGHT METAL ROOFING COMPANY, OF PHILADELPHIA, PA.

METALLIC ROOFING-PLATE OR SHINGLE.

SPECIFICATION forming part of Letters Patent No. 358,595, dated March 1, 1887.

Application filed January 3, 1887. Serial No. 223,223. (No model.)

To all whom it may concern:

Be it known that I, LEWIS D. CORTRIGHT, of Hyde Park, Cook county, Illinois, have invented a new and useful Improvement in Metallic Roofing-Plates or Shingles, of which the following is a true and exact description, due reference being had to the accompanying drawings, which form part hereof.

My invention relates to the construction of what are generally known as metallic shingles for roofing, these shingles consisting of small metallic plates adapted to be secured to the boarding of a roof by nailing in the same way as wooden shingles or slates.

15 The object of my invention is to provide a lock-joint and gutter for such metal shingles by which the entrance of water through the vertical joints onto the boarding of the roof will be effectually prevented, while at the same time the vertical edges of adjoining shingles are properly united and aligned.

Reference being now had to the drawings which illustrate my invention, Figure 1 is a perspective view of a number of my improved shingles as applied to a roof, and Fig. 2 an end view of two of my shingles interlocked and secured to the roof-boarding.

20 A A' A' are my improved shingles, the opposite vertical edges of which are bent, as shown at B and C. The edge C of my shingle is bent so as to form the square hook D d out of the double thickness of the metal, and the sheet is then carried outward on the plane of the main surface A to a point some distance beyond the point d of the hook, where an upward bend is made in the metal to form the projection F, the metal being carried sufficiently beyond this projection to form a nailing-flange, G. The edge B of my shingle is 25 bent upward at J, so as to fit or hook over the projection F, and terminates in another upward bend or hook, I, adapted to fit under the downwardly-projecting point d of the hook D d.

25 K represents the supporting-boards to which the shingles are nailed; H, a nail for securing the nailing-flange G to the support, while L is the usual projection formed in the bottom of the center of each shingle to accommodate

the elevated seam of the lower shingles and so allow the upper plates to rest closely upon the lower ones.

In laying my shingles, constructed as shown in the drawings, the left-hand shingle is first secured to the roof by the nailing-flange G. 35 The hook I of the next shingle to the right is then inserted under the point d, and the shingle then turned downward on this edge as a hinge until the projection J fits over the projection F of the lower shingle, and the right-hand shingle then lying flat upon the roof is nailed down in the same way as the one to the left. The natural spring of the metal will cause the bottom of the hook I to fit tightly against the point d and the top of the projection J to press upon the top edge of F, so that my construction insures two points or rather lines of close contact in the side joints of my shingles. The large open space E, formed in the edge C by the hook D d and the projection F, and closed by the edge B of the adjoining interlocked shingle, affords an ample and free passage or gutter for any water that may enter the seam formed by the point d and the hook I, the projection F serving as a dam 45 to prevent the water getting onto the nailing-flange, and thence to the boards K. As is shown, the gutter E in each case opens freely upon the center of a shingle in the row below.

It is evident that my improved seam and 50 gutter can be used with oblique as well as vertical joints, and of course the shape of the hook D d may be varied, the square shape shown being, however, preferred by me. The proportions of the various parts of my seam 55 may also be varied; but in all cases the distance between the point d and the projection F must be sufficiently great to allow of the insertion of the bent edge B by the folding operation described. 60

Having now described my invention, what I claim as new, and desire to secure by Letters Patent, is—

1. As a new article of manufacture, metallic roofing-shingles having an edge, C, provided 65 with a hook, D, having a downwardly-projecting point, d, and a projection, F; and flange G beyond said point, and an opposite

edge, B, having a projection, J, and hook I, adapted to interlock with the point d and projection F of a similar shingle.

2. In metallic shingles, substantially as shown and described, the combination, with the hook D d, formed in one edge of the shingle, of the open space E, adapted to extend

back of the interlocked edges of the adjoining shingle and form an unobstructed gutter, substantially as shown and described.

LEWIS D. CORTRIGHT.
